ELECTRIC CABLE AND METHOD OF
MANUFACTURING IT

Roy F. Layton, Newark, N. J., assignor to Western Electric Company, Incorporated, New York, N. Y., a corporation of New York

Application June 23, 1932, Serial No. 618,831

8 Claims. (Cl. 173—266)

The invention relates to an electric cable and method of manufacturing it and more particularly to the type of cables employed in transmitting intelligence electrically.

5 Objects of the invention are to provide an improved electric cable and a method of forming the cable.

In the prior art it has been the practice in some instances in connection with the manufacture of 10 cables for transmitting intelligence electrically to form the cable by stranding pairs of paper insulated conductors together, binding the conductor pairs in a group and finally extruding a sheath of lead or lead alloy over the insulated 15 conductors.

If in place of the lead sheath a thin metal sheath of copper, brass, zinc, or similar metal is applied as a tape directly over a group of assembled conductors having its abutting edges secured 20 in a manner to provide a water-proof cable joint, the tape may have a tendency to rip and crack if the assembled cable is flexed beyond certain limits.

25 According to one embodiment of the invention herein illustrated and described, a flexible cable for transmitting intelligence electrically is constructed by forming pairs of paper insulated conductors, binding the pairs of conductors into a 30 group, covering the group with a layer of paper applied spirally, applying a layer or layers of metal tape spirally around the conductor core, applying a continuous thin metal tape or skelp over the spirally wound tape, soldering or otherwise 35 joining the edges of the continuous metal tape or skelp together to form a water-tight cable, and applying a suitable protective coating over the continuous tape such as rubber or a wrapping of textile material impregnated with a 40 preserving material.

Other objects and advantages of the invention will appear from the following description when considered in connection with the accompanying drawing in which

45 Fig. 1 is a plan view partially in section of one embodiment of the invention;

Fig. 2 is a plan view partially in section of another embodiment of the invention;

50 Fig. 3 is a plan view, partially in section, of still another embodiment of the invention;

Fig. 4 is a vertical sectional view along the line 4—4 of Fig. 1;

55 Fig. 5 is a vertical sectional view along the line 5—5 of Fig. 2, and

Fig. 6 is a vertical sectional view along the line 6—6 of Fig. 3.

Referring to Figs. 1 and 4 of the drawing, a plurality of conductors 10, preferably of copper and having low resistance, insulated with paper, textile or other suitable material, are stranded together loosely in layers to form a group or bundle 12. The group or bundle 12 may be formed in any suitable manner, but preferably by the usual and well known form of strander which 10 has associated therewith a tape serving head by which a paper wrapping 13 may be applied spirally to retain the group comprising the conductors within a predetermined diameter. Surrounding the paper wrapping 13 is a flexible 15 sheath 15 which is formed by applying a comparatively thin metallic tape or ribbon helically or spirally around the cable so that the edges of adjacent turns slightly overlap each other. The flexible sheath 15 may be composed of a lead 20 alloy, brass, copper, zinc or other suitable material. Surrounding the flexible metal sheath 15 is another flexible metallic sheath 20 formed into the shape of a tube from brass, copper, zinc or 25 other suitable metallic tape or skelp and having its edges 21 overlapped and joined. The edges 21 may be joined by soldering, brazing, welding, or by other suitable methods. If desired, the lap shown may be omitted and edges 21 of the sheath 20 may be formed to abut each other and secured 30 together by any suitable means well known in the art, such as soldering, brazing or welding, to form a water-proof joint.

Over the metal sheath 20 a suitable protective 35 coating 25 is preferably applied. The protective coating 25 may be composed of materials such as tough rubber, gutta percha, gutta percha substitute or other suitable material applied by forcing the cable through an extruding machine of 40 any suitable type well known in the art which applies the covering in one or more layers around the entire length of the cable, or the protective coating may take the form of a textile material impregnated with a suitable preserving compound 45 preferably such as asphalt flooded burlap wrapped around the cable and covered with a layer of paper 26 spirally applied over the textile material. The textile material may be impregnated either before or after being applied to the cable and 50 the preserving compound may be asphalt or other suitable compound capable of resisting chemical decomposition and also serving as a mechanical reinforcement for the cable.

In some cases it may be advantageous to em- 55

ploy a cable constructed as shown in Figs. 2 and 5 having two or more layers 15 and 16 of metallic sheath applied over the paper wrapping prior to the application of the continuous tape or skelp 5 which forms the water-tight tube 20. The additional layer or layers 16 are preferably composed of material similar to that of the metallic tape 15. The layer of metallic tape 16 may have the same direction of lay as the layer 15 or the 10 opposite direction as shown in Fig. 2 and the edges may overlap as shown in Fig. 2 or the tape 16 may be applied in a manner similar to that described below in connection with Fig. 3.

In an alternate method of constructing the 15 cable as shown in Figs. 3 and 6 the layer or layers of flexible sheath between the paper 13 and the water-tight sheath 20 may be formed and applied to provide an intermittent support for the sheath 20 and may take the form of a tape or wire 17, somewhat thicker than the water-tight sheath 20, or deformed by embossing or corrugating and applied over the paper wrapping 13 in a manner such that there is an intervening space between the edges of the tape or wire 17, or between the ridges of the bosses or corrugations.

The above described methods of forming an 20 electric cable provide a flexible cable which when flexed will cause the sheath 20 to crinkle uniformly and the finished cable can withstand many flexures and may be flexed to a greater degree without the tendency of the water-tight sheath 20 to rip or crack.

It is to be understood that the invention is not 25 to be limited to the particular embodiments shown, nor to the particular arrangements that have been described and shown in detail, but only by the scope of the appended claims.

What is claimed is:

1. In an electric cable having an inner insulated conductor portion, a covering of paper ribbon applied spirally around the conductor portion, a metallic ribbon applied spirally around the paper ribbon, a thin metallic sheath applied over 30 said metallic ribbon formed from sheet metal and having its edges joined to form a water-proof casting, a sheath of asphalt flooded burlap over said metallic sheath and a covering of paper ribbon applied over said asphalt flooded burlap.

2. In an electric cable having an inner insulated conductor portion, a covering of paper ribbon applied around the conductor portion, a metallic ribbon applied spirally around the paper ribbon and having its edges overlapped, a metallic waterproof sheath applied over said metallic ribbon, a wrapping of textile material impregnated with preserving material over said metallic sheath, and a covering of paper applied over 45 said impregnated textile material, said metallic waterproof sheath comprising a comparatively thin sheet of a metal selected from the class which consists of copper and brass and zinc, the edges of which are joined together in a seam extending longitudinally of the cable.

3. In an electric cable having an inner insulated conductor portion, a covering of paper applied around the conductor portion, a relatively thick metallic ribbon applied spirally around the paper covering, a relatively thin metallic waterproof sheath applied over said metallic ribbon, a wrapping of textile material impregnated with preserving material over 50 said metallic sheath,

and a covering of paper applied over said impregnated textile material, said metallic waterproof sheath comprising a comparatively thin sheet of a metal selected from the class which consists of copper and brass and zinc, the edges 5 of which are joined together in a seam extending longitudinally of the cable.

4. In an electric cable having an inner insulated conductor portion, a covering of paper ribbon applied around the conductor portion, a plurality of layers of metallic ribbon applied spirally around the paper ribbon, a metallic waterproof sheath applied over said metallic ribbon, a sheath of asphalt flooded burlap over said metallic sheath, and a covering of paper applied over 10 said asphalt flooded burlap.

5. In an electric cable having an inner insulated conductor portion, a covering of paper ribbon applied around the conductor portion, a plurality of layers of metallic ribbon applied spirally around the paper ribbon the alternate layers of metallic ribbon having opposite directions of lay, a metallic waterproof sheath applied over 15 said metallic ribbon, a sheath of preservative flooded textile over said metallic sheath, and a covering of paper ribbon applied over 20 said preservative flooded textile, said metallic waterproof sheath comprising a comparatively thin sheet of a metal selected from the class which consists of copper and brass and zinc, the edges of which 25 are joined together in a seam extending longitudinally of the cable.

6. In an electric cable having an inner insulated conductor portion, a covering of paper ribbon applied around the conductor portion, a relatively thick metallic ribbon applied spirally around the paper ribbon with an intervening space between the edges of the metallic ribbon, a relatively thin metallic waterproof sheath applied over 30 said metallic ribbon, a sheath of asphalt flooded burlap over said metallic sheath, and a covering of paper ribbon applied over 35 said asphalt flooded burlap.

7. In an electric cable having an inner insulated conductor portion, a covering of paper ribbon applied spirally around the conductor portion, a metallic tape applied spirally around the paper ribbon with an intervening space between the adjacent outermost portions of the tape, a metallic waterproof sheath applied over 40 said metallic ribbon, a sheath of asphalt flooded burlap over 45 said metallic sheath, and a covering of paper ribbon applied over 50 said asphalt flooded burlap.

8. In an electric cable having an inner insulated conductor portion, a covering of paper applied around the conductor portion, a metallic ribbon applied spirally around the paper covering, a relatively thin metallic waterproof sheath applied over 55 said metallic ribbon, a wrapping of textile material impregnated with preserving material over 60 said metallic sheath, and a covering of paper applied over 65 said impregnated textile material, said metallic waterproof sheath comprising a comparatively thin sheet of metal selected from the class which consists of copper and brass and zinc, the edges of which are joined together and the seam resulting from the edge joining operation extending longitudinally of the 70 cable.
